(57) **CLAIM**

The ornamental design for a folding ladder as shown and described.

DESCRIPTION

FIG. 1 is a front, left and top side perspective view of a folding ladder showing our new design;
FIG. 2 is a rear, right and bottom side perspective view thereof;

FIG. 3 is a front elevation view thereof;

FIG. 4 is a rear elevation view thereof;

FIG. 5 is a left side elevation view thereof;

FIG. 6 is a right side elevation view thereof;

FIG. 7 is a top plan view thereof;

FIG. 8 is a bottom plan view thereof;

FIG. 9 is an enlarged partial view of FIG. 1;

FIG. 10 is an enlarged partial view of FIG. 2;

FIG. 11 is a view of the product in changed state of FIG. 1;
FIG. 12 is another view of the product in changed state thereof;

FIG. 13 is another view of the product in changed state thereof; and,

FIG. 14 is another view of the product in changed state thereof.

The broken lines in the drawings depict portions of the folding ladder that form no part of the claimed design. The long-short dash broken lines depict the boundaries of the detail enlargements that form no part of the claimed design.

1 Claim, 14 Drawing Sheets
